ROAD MARKER

Filed July 18, 1941

INVENTOR
MYRTIL SCHWARTZ

BY *Leon M. Strauss*

1. A road marker comprising a block having a top surface, a bottom surface, and a side surface, said block being made of a material which is tough, durable, and somewhat yieldable to pressure, and which is skid and slip retardant to render the marker safe for use on roads, streets, and highways.

2. A road marker comprising a block having a top surface, a bottom surface, and a side surface, said block being made of a material which is tough, durable, and somewhat yieldable to pressure, and which is skid and slip retardant to render the marker safe for use on roads, streets, and highways.

UNITED STATES PATENT OFFICE

2,368,330

ROAD MARKER

Myrtis Schwartz, New York, N. Y.

Application July 18, 1941, Serial No. 402,913

1 Claim. (Cl. 94—1.5)

This invention relates to road markers and deals more particularly with markers for the guidance of both vehicular and pedestrian traffic.

The main object of the invention is to provide a road marker which may be set and embedded into the surrounding pavement in a manner to obviate displacement due to the stresses and forces caused by vehicles passing thereover.

Another object of the invention is to provide a marker which is so formed that a plurality thereof may be arranged in interlocking association to form a traffic guiding line or a surface having significance to motorists and pedestrians.

A further object resides in the provision of a road marker provided with means for effectively keying said marker in the surrounding pavement without resort to separate and special plates, hooks, or bolts commonly employed for this purpose.

A still further object is to provide a road marker which is practically indestructible despite the great forces to which it is subjected and compressible to some degree to yield to said forces, the invention contemplating the use of a material which also imparts non-skid properties to the marker, said properties also obviating slipping of pedestrians thereon.

The foregoing objects and other objects, features and advantages of the invention will be pointed out or will become clearly evident from the following detailed description of the invention as embodied in the accompanying drawing. In said drawing, which illustrates several preferred forms of the invention:

Fig. 1 is a perspective view illustrating the manner of use of road markers contemplated herein.

Fig. 2 is a perspective view of a preferred form of road marker.

Fig. 3 is a cross-sectional view thereof, taken along line 3—3 of Fig. 1.

Fig. 4 is a sectional view of an alternate form of road marker.

Fig. 5 is a perspective view thereof.

Fig. 6 is a similar view, as seen from the bottom, of yet another form of road marker.

In that form of the invention which is shown in Figs. 1, 2 and 3, the marker 10 is made of a natural or synthetic rubber composition whereby it is tough, durable, and somewhat yieldable to pressure. The material employed is also preferably skid and slip retardant to render the marker safe for use on roads, streets, and highways.

In the form under discussion, the marker is preferably made with a top surface 11 which may

have painted or formed thereon certain markings or indicia such as shown at 13. The bottom surface 14 of the marker is preferably formed with undercut grooves 15 which may be arranged transversely to the direction of the forces to which the marker is subjected or, as shown, said grooves may be interconnected to form a rectangle inclosing the central portion 16 of the marker. This latter portion may serve to carry the manufacturer's data which may be embossed on said bottom surface. It is preferred, however, to recess this data bearing portion as at 17 to provide further effective keying means which, together with the grooves 15, serve to obviate lateral displacement of the marking in its surrounding medium. This medium, shown at 18, may be concrete, asphalt, cement, or any of the well-known materials used on streets, roads, and highways.

As shown in Figs. 1 and 2, this form of the invention is formed as a block having castellated sides. On two adjacent sides, the castellations form alternate tenons 19 and recesses 20. On the other two adjacent sides, they form the alternate tenons 21 and recesses 22. In this manner, the opposed sides of the marker are different in that the tenons of one side are aligned with the recesses of the opposite side. The purpose of this arrangement becomes apparent from perusal of Fig. 1 which shows several markers arranged in interlocking relation to form a line of such markers. The tenons 19 of one marker fit into the recesses 22 of the adjacent marker on one side thereof, and the tenons 21 fit into the recesses 20 of a marker on the other side thereof. Similarly, as shown by the dot-dash lines of Fig. 1, the tenons 19 and 21 may fit the respective recesses 22 and 20 should the arrangement be transverse to that shown in full lines.

It is obvious that a marker 10 may be set into the pavement 18 without reference to other markers, in which case the tenons and recesses thereof will serve as effective keying means to obviate rotational movement of said marker due to torsional stresses caused by a force applied at one corner thereof.

The structure of Fig. 2 may be varied to include a peripheral groove such as shown at 23 of Figs. 4 and 5. This peripheral groove interconnects with the recesses 20^a and 22^a to provide the tenons 19^a and 21^a. In this manner a further effective keying means, comprising particularly the lower tenons 19^a and 21^a, is provided to prevent undesired upward displacement of the marker from its surrounding medium.

A further modification of the invention is shown in Fig. 6 wherein the peripheral keying groove 23^b is retained and the recesses 20 and 22, and 20^a and 22^a eliminated to provide top and bottom flanges on the marker, respectively 24 and 25. In other respects this marker may follow those above described.

While the invention is of relatively simple nature, it does represent an improvement which is capable of being practiced in other ways than those described. It is intended, therefore, that the spirit and scope of the invention as claimed be not unduly limited by the instant specific disclosure which is for explanatory purposes only.

I claim:

A road marker comprising a substantially square-shaped block adapted to be set into pavement and with its substantially flat surface flush

with the surface of the pavement, and means on said block having keying engagement with said pavement and adapted to interlock with similarly shaped adjacent blocks, said means comprising spaced pairs of alternate tenons and recesses provided between the surface and underface of said block at the peripheral side walls thereof, a groove extending between said pairs of tenons and lengthwise around said side walls of said block, the tenons on one side wall being alignedly arranged with the recesses on the opposite side wall, said pairs of tenons being coextensive with one another, and one or more projections provided on said underface of said block to prevent displacement of said block at its location in said pavement.
